[57] CLAIM

The ornamental design for a customer interface module for fuel dispenser, as shown and described.

DESCRIPTION

FIG. 1 is a right front perspective view of a customer interface module for a fuel dispenser showing our new design;

FIG. 2 is a front elevational view thereof;

FIG. 3 is a second front elevational view thereof; and,

FIG. 4 is a second right front perspective view thereof.

The broken lines showing the hoses and fuel dispenser of the customer interface module for fuel dispenser in all of the drawing figures is for illustrative purposes only and forms no part of the claimed invention.
